FOREIGN PATENT DOCUMENTS

CN 301445176 * 1/2011

Primary Examiner — Shawn T Gingrich*Assistant Examiner* — Justin M. Donaldson(74) *Attorney, Agent, or Firm* — K&L Gates LLP(57) **CLAIM**

The ornamental design for a housing for a full phase module gate drive, as shown and described.

DESCRIPTION

FIG. 1 is a perspective view of a housing for a full phase module gate drive;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines in the drawings are for the purpose of illustrating portions of the article that form no part of the claimed design.

1 Claim, 7 Drawing Sheets(56)
